UNITED STATES PATENT OFFICE.

NICOLAS EMILIE MATHLIN, OF PARIS, FRANCE, ASSIGNOR TO SCHNEIDER & CIE., OF PARIS, FRANCE, A LIMITED JOINT-STOCK COMPANY OF FRANCE.

AUTOMATIC GUN.

Application filed October 27, 1926, Serial No. 144,559, and in France January 22, 1926.

The present invention relates to an automatic gun of the type of those which, during firing, recoil in a cradle, the gun comprising, like other known automatic guns, a mechanism for opening and closing the breech, a firing mechanism, a cartridge distributing mechanism, a mechanism for ramming the cartridges into the bore of the gun barrel and a device for ejecting spent cartridge cases, all these mechanisms and 10 this device operating automatically by means of the energy taken from the recoil of the gun barrel in its cradle.

The new gun has been designed in such 15 a way as to be adapted to work normally as an automatic gun, while for firing a first projectile it is possible without any great effort to actuate, by simple manipulation of a member such as a handle or a lever, all the 20 mechanisms, which, for firing the subsequent projectiles, operate automatically.

The firearm has further been designed in such a way that it is possible, still by the simple manipulation of a member such as 25 a lever or a handle, to carry out continuous firing or intermittent firing shot by shot, that is to say, at intervals varied as desired.

The construction of the firearm is finally 30 designed not only with a view to obtaining the various functions enumerated above but in such a way that, with a view to making it possible to increase the speed of firing the recoil will be as small as possible, and that the forces to which the mechanisms are subjected 35 remain practically constant in spite of the variations in the speed of the gun barrel during the recoil and the re-entry into battery position.

The firearm comprises, like other known 40 automatic guns, a cover or casing projecting to the rear upon the breech, but according to the invention this casing is made movable longitudinally, for example upon guides projecting upon the cradle by means 45 of a mechanism actuated by a simple handle, relatively to the gun barrel at rest, while normally the said casing remains stationary while the gun barrel moves relatively to it by recoiling in its cradle and by 50 re-entering into battery position.

In order that this mobility may be obtained by simple means, which, at the same time produce a very small recoil, the move-

ments of the breech block and those of the cartridge distributor are, according to the 55 invention, produced by guide cams upon or in which move rollers, these members (guides and rollers) being carried respectively, the ones by members movable with the gun barrel, the others by the movable 60 casing. As described hereinafter by means of the suitable profiles of the guides the force developed upon the recoil for the operation of the corresponding mechanisms remains practically constant during the 65 whole of this operation in spite of the variations in the speed of recoil.

A practical form of the invention is illustrated by way of example in Figures 1 to 70 9 in the accompanying drawings.

Fig. 1 is a plan section along the axis of the gun barrel showing the whole of the back part of the firearm, that is to say, that part which comprises all the new characteristic devices of the invention. 75

Fig. 2 is a corresponding longitudinal sectional elevation.

In these two first figures the members are shown in an intermediate position of operation a moment before the cartridge is 80 rammed into the bore of the gun barrel.

Fig. 3 is a longitudinal elevation of a part of the firearm corresponding to Figs. 1 and 2.

Fig. 4 is a sectional elevation of a part 85 similar to that shown in Fig. 2 and showing the firearm loaded, the breech closed, with the members in the firing position.

Fig. 5 is a similar longitudinal sectional elevation to that shown in Figs. 2 and 4 the 90 members being shown in the position they occupy towards the end of the recoil, the breech being at this moment completely open and the spent cartridge case in process of ejection. 95

Fig. 6 is a plan view seen from above with a part in section taken along the line 6-6 in Fig. 7, which is a cross section along the line 7-7 in Fig. 5.

Fig. 8 is a sectional elevation along the 100 line 8-8 in Fig. 1.

Fig. 9 is a back elevation of a part.

Figs. 10 to 35 illustrate a special form of the invention. This form enables firing to be speeded up particularly on account of the 105 fact that the spent cartridge case can be

ejected at the same time that a live cartridge is being loaded onto the ramming in tray. Further, the mechanism actuating the casing comprises a recuperating device which is compressed once by the firing of the first projectile of the loading belt and remains engaged during the firing of the following shots, thus storing up the required energy for producing the forward and return motion of the loading device when the projectiles of a loading element, having been used up, this element is replaced by a new one.

Fig. 10 is a longitudinal sectional elevation showing the firearm at rest before the firing of a first projectile.

Fig. 11 is a similar sectional elevation showing the casing brought forward into contact with the cradle with a view to loading a first projectile.

Fig. 12 is a similar section showing the casing moved back again either by hand for firing a first projectile or automatically during the consecutive firing of several loading elements, this return movement having produced the rotation of a loading element with a view to bringing the new projectile into position so as to become engaged in the loading spoon or tray.

Fig. 12 shows a projectile loaded upon the tray and upon the point of being driven into its lodgment as a result of the ramming in action of the tray.

Fig. 13 is a similar sectional elevation showing the projectile when it has reached a point near the end of its travel for engagement in the chamber of the gun barrel.

Fig. 14 is a plan section taken along the line 14-14 in Fig. 12.

Fig. 15 is a cross sectional elevation taken along the line 15-15 in Fig. 11, the new projectile being, however, not yet engaged in the loading tray.

Fig. 16 is a similar cross section showing the members in another position of operation.

Fig. 17 is a cross sectional elevation of a part taken along the line 17-17 in Fig. 13.

Fig. 18 is a plan section of a part taken along the line 18-18 in Fig. 10.

Fig. 19 is a cross sectional elevation of a part taken along the line 19-19 in Fig. 10.

Fig. 20 is a plan section of a part taken along the line 20-20 in Fig. 19.

Fig. 21 is an end elevation showing a loading element and the duct for the ejection of a spent cartridge case.

Figs. 22 and 22^a, 23 and 23^a and 24 show in elevation, in plan section and in cross section along the line 24-24 in Fig. 23 respectively a mechanism enabling the forward and return movement of the casing to be obtained either by hand with a view to firing a first projectile, or automatically by the recuperating device each time the projectiles of a loading element have all been employed.

Fig. 25 is a cross section showing a detail of a part of the mechanism taken along the line 25-25 in Fig. 10.

Fig. 26 is a cross section of a part taken along the line 26-26 in Fig. 19.

Figs. 27 and 28 are similar sections to that shown in Fig. 19 showing the members in different working positions.

Figs. 29, 30 and 31 are elevations showing details of one of the escapement devices which the mechanism for rotating the cylinder comprises.

Fig. 32 is a plan view of the anchor of this escapement.

Fig. 33 is a section taken along the line 33-33 in Fig. 29.

Fig. 34 is a similar sectional elevation of a part to that shown in Fig. 19, the members being shown in another working position.

Fig. 35 is a cross section taken along the line 35-35 in Fig. 19.

In Figs. 1 to 9, A is the tube or gun barrel proper arranged so as to move during recoil, in a cradle B. The latter is provided with frame plates B¹ extended towards the rear in such a way as to form supports or guiding members (Figs. 7 and 8) for a casing C itself serving, in the known manner, as support and guide for the loading belt D of a cartridge supplying mechanism.

According to one of the essential features of the invention this casing may be made movable relatively to the cradle for firing a first projectile. For this purpose instead of being rigidly secured to the cradle it is connected to the latter by a kinematic connection which comprises, for example, a shaft b turning in bearings b¹ mounted upon the cradle, and at one of the ends of which is keyed a pinion b² engaging with a wheel b³, the shaft b⁴ of which is also carried by the cradle. The wheel b³ is rigidly secured by a crank b⁵ to the pin b⁶ which is pivotally connected to one end of a rod E, the other end e¹ of which is pivotally connected to the casing C. This kinematic connection may, if desired, be rendered stationary or rendered free for a displacement of the casing towards the cradle; the said connection comprises for this purpose an operating lever or handle b⁷, the pin of which is adapted to be engaged in a catch b⁸ formed upon the cradle.

The casing C thus constructed for its displacement by hand towards the cradle, with a view to firing a first projectile, and for rendering it stationary relatively to the cradle with a view to the continuous firing of the subsequent projectiles, is further designed in such a way as to render as easy as possible the relative movements between it and the gun barrel, which movements produce the automatic operation of the various mechanisms for opening and closing the breech, for firing the gun, for ejecting the spent cartridge cases and for distributing the

cartridges. For this purpose the movements of the breech block and those of the cartridge distributor are produced by guide cams upon or in which move rollers, these members (rollers and guides) being carried respectively, the ones by members movable with the gun barrel, the others, that is to say, the complementary members by the casing which acts as support for the distributor and lodgment for the ramming in mechanism.

In the example shown in Figs. 1 to 9 the breech block F is constructed in the manner known in itself, in the form of a wedge or block movable in vertical grooves α upon the gun barrel. It is provided at its lower part with a carriage bar F¹ provided with rollers f¹ which when at rest (Fig. 4) are in contact with guides C¹ formed upon the casing. The carriage bar serves for the attachment of pistons F² which form, in the manner known in itself, the elements of a spring recuperator adapted to produce the automatic closure of the breech, these elements being located in sleeves F³, themselves secured in lodgments provided in the gun barrel A.

The guides C¹ which control the opening of the breech under the effect of the recoil of the gun barrel are placed in such a way that this opening commences to be produced as soon as the recoil begins and they are further shaped in such a way that the force developed for opening the breech remains practically constant during the whole of the movement of withdrawal. On account of the fact that the guides produce the opening movement from the beginning of the recoil this movement takes place in the shortest possible time and as the origin of the guides is for this purpose situated in the immediate neighbourhood of the front face of the casing the latter may be as small in length as possible and only extended to the rear of the breech a distance little greater than the length of the projectile.

Finally the movement of withdrawal of the breech block by means of the rollers of the carriage bar and the guides formed upon the casing, which device comprises no kinematic connection and consequently obviates the play and inertia inherent to such connections, facilitates the reversibility of the displacement between gun barrel and casing for firing the first projectile.

Such a conjugation by means of guide and roller is established between the gun barrel and the member for advancing the loading belt carried by the casing. This connection may be formed by an arm G (Fig. 2), rigidly secured to the gun barrel or preferably pivotally connected at g to a support a¹ formed upon the latter. This arm is guided upon the casing C and has formed in it a horizontal slideway forming a guide cam for a roller h pivotally

mounted upon a carriage H adapted to run by means of rollers h¹ upon a track at right angles to the axis of the gun barrel and formed at the upper part of the casing C.

The carriage H forms the guide for the spring pin H¹ adapted to carry along the loading belt D. In the arm G is also formed a vertical slideway g² forming a guide cam for a roller i carried by one of the arms of a rocking lever I¹—I² pivotally connected at a fixed point c¹ to the upper part of the casing C. The arm I² of the rocking lever is provided at its free end with a slot i² in which engages a pin i³ forming a projection upon the socket I³ which forms part of a compressible push piece I. The movements of this push piece are constantly tied to those of the arm G, this connection being, as mentioned above, established by the roller i and the vertical guide g². In order to permit the push piece to yield under an abnormal pressure exerted in an upward direction this push piece is hooked on to a rod I⁴ movable in the socket I³ and normally held pressed upon the end of this socket by a spring i⁴, one end of which presses upon the head of the push piece and the other upon the end of the socket. The spring may be held guided by its lower part in a socket I⁵ rigidly secured to the push piece proper I.

Upon the inner face of the transverse walls in front and behind the cover of the casing C are mounted respectively rollers c², c³ serving for the guiding of longitudinal troughs d¹, d², d³ of the loading belt D.

A loading spoon J forming a ram becomes hooked upon recoil upon the displaceable casing C by means of a beak or catch j, which loading spoon is carried for this purpose by a spring recuperator K pressing upon the rear end of the casing and becoming cocked upon recoil. The spoon J is guided vertically in the recuperator K by flanges j¹ (Fig. 7) and is normally held raised by blade springs j², one end of which is attached to the cover of the recuperator K.

The spoon is provided with a pusher pin J¹. A small swinging shutter J² is pivotally connected to the spoon J and is normally held raised, the depression of which shutter, with a view to ejecting the cartridge being effected by means of a transverse locking bolt J³, when the latter encounters an incline c⁵ formed upon the casing (Fig. 7). The connection between the shutter J² and the locking bolt J³ is obtained by means of a pin j³ engaging in a notch in the locking bolt. A spring buffer L for ejecting the spent cartridge cases is provided in the rear end of casing C, said buffer being located in the horizontal axial plane of the gun barrel and at one side of the longitudinal axis of said barrel.

The firing mechanism comprises a locking bolt M movable in a direction parallel to the

- axis of the gun barrel in a guide B^2 carried by the cradle. This locking bolt is arranged to penetrate into an opening f formed in the breech block F . This bolt, from which the breech block becomes separated as a result of the recoil of the gun barrel becomes re-engaged automatically towards the end of the re-entry into battery when the breech block is brought back into the closed position and it acts in this movement of re-engagement through a suitable transmission $N-O$ of known type upon the striker P causing the latter to be projected upon the primer of the cartridge.
- The bolt M may be actuated by a bell crank lever M^1-M^2 pivotally connected to the cradle, under the action of which lever it becomes withdrawn when, with a view to firing a first projectile, the casing C is moved toward the cradle. In this movement of displacement a spring push piece Q , carried by the casing acts by means of an incline q upon a roller m carried by the branch M^2 of the bell crank lever M^1-M^2 . The push piece Q may be displaced relatively to the casing C in order to be brought into the position shown in full lines in Fig. 1 where it forms an abutment stop for limiting the travel of the bolt M , thus preventing the production of the automatic firing. This firing may however be then carried out by hand for firing the gun shot by shot by means of a transmission comprising a handle R , acting upon a pin r engaging in a suitable notch or opening in the push piece Q by rotating handle R it is possible as desired to bring the incline q of the push piece into a position of withdrawal or to bring it into a position in which it acts upon the bell crank lever M^1-M^2 . When the push piece Q is moved by means of handle R into engagement with the bell crank lever the spring associated with bolt M is rendered ineffective to actuate the latter.
- For the purpose of describing the operation of the firearm it will be assumed first of all that the latter has been loaded by a preliminary operation which will be described hereinafter and that the members are in the position shown in Fig. 4 in which the breech block, having been brought back into its closed position by the re-entry into battery, the bolt M has struck the lever N of the firing mechanism causing the striker P to be projected on to the primer of the cartridge through the medium of the lever O .
- As soon as the recoil of the firearm commences under the action of the pressure of the gases from the charge the breech block F is compelled by the rollers f^1 to follow the guides C^1 of the casing and thus to open gradually by sliding in the grooves a of the gun barrel, while the springs f^2 becomes compressed as a result of the descent through F^1 .
- ³ As mentioned above the profile of the guides

C^1 is such that the forces withdrawing the breech block remain constant in spite of the variations in the speed of the gun barrel during recoil.

The recoil of the gun barrel produces at 70 the same time the rearward displacement of the arm G and, consequently the displacement of the guides g^1, g^2 which control respectively the rollers h and i . The displacement of the roller h produces a displacement 75 of the carriage H and of the spring pin H^1 . This displacement has the effect of bringing the pin H^1 from the position it occupies in Fig. 7, where it is in contact with a projecting piece d^4 of the belt, into a position 80 further to the right where the pin H^1 , by sliding by means of its bevelled bead, upon the projecting piece d^5 , has become engaged behind the latter. During this time the roller i has been displaced by the guide g^2 85 in such a way as to pass from the position it occupies in Figs. 2 and 7 into that which it occupies in Fig. 5 which shows it in its slideway when the gun barrel has nearly completed its recoil. This displacement 90 makes the rocking lever I^1-I^2 swing, raising the arrangement $I-I^3-I^4-i^4$ which forms the cartridge pushing mechanism, into the position shown in Fig. 5.

Still during the recoil the swinging of the arms S of the extractor as a result of a flange or rim f^8 of the breech acting upon the end s of these arms causes the cartridge case to be extracted (Fig. 5). Further the gun barrel at the commencement of the recoil presses upon the pin K^1 (Fig. 4) then upon the front end of the sleeve K^2 , thus compressing the recuperator spring K and carrying the spoon J backwards. The latter at the end of the recoil becomes engaged 105 by means of the beak j upon the casing C (Fig. 2).

At the end of the recoil the spent cartridge cast T is violently driven backwards and projected against the spring buffer L which, since it is placed eccentrically relatively to the axis of the gun barrel, causes the cartridge to pivot towards the lateral escapement duct C^2 (Fig. 9) formed in the casing. The shutter J^2 which completes the guiding of the cartridge while it is being rammed into the bore of the gun barrel, is withdrawn by being lowered in order to allow the spent cartridge case to fall and is then brought back into its normal position by the action of the spring j^4 . When the recoil is completed the roller f^1 will have reached the position shown in dot and dash lines in Fig. 5. The recuperator of the gun barrel, one of the members of which is shown at U enters into action; the arm G is thus moved forward with the gun barrel and it thus displaces in the slideways g^1, g^2 respectively the roller h and the roller i . The displacement of the roller h and consequently 120

110

115

120

125

130

that of the carriage H and of the spring pin H¹ and by means of this the translation of the loading belt D has finally the effect of bringing a new cartridge T into line with the axis of the gun barrel. The cartridge thus displaced is immediately beneath the cartridge pusher which is then raised into the position shown in Fig. 5.

During this time the breech block F is raised by its spring recuperators F²—f², till the block abuts by means of end pieces f⁴ against the beaks of the extractor arms S (Figs. 2 and 8). The gun barrel continues to make its movement of re-entry into battery and the guide cam g², by acting upon the roller i compels the branch I¹ of the rocking lever I¹—I² to become raised, the effect of which is to drive the cartridge pusher downwards and project the cartridge T on to the spoon J, extracting it from between the flexible retaining jaws and thus bringing it from the position shown in Fig. 5 into that shown in Fig. 2. Under the effect of the weight of the cartridge T the spoon J descends, compressing the spring f², the effect of which is to release the spoon from its engagement with the casing C. As soon as this disengagement has been produced the recuperator spring K can extend, carrying along the spoon J and the cartridge T longitudinally by means of the pin J¹. The projectile which bears at its front end upon the loading tray V is thus driven into the chamber of the gun barrel without it being accompanied as far as the end of the travel by the ramming in beak J¹ the forward movement of the projectile being obtained by the effect of the sudden expansion of the springs K.

At the end of this ramming in movement the rim t of the cartridge case encounters the lateral ribs s¹ of the flexible arms and causes the latter to swing forward, any backwards movement of the cartridge in particular when firing at high angles of elevation, being prevented by a retaining pin W pivotally connected to the breech, a flat spring w constantly tending to raise the said pin. The breech block F having been released from its securing means by the withdrawal of the extractor arms S is brought back into the closed position by the action of the recuperating springs f². The locking bolt M which was withdrawn by the pressure of a solid part of the breech block during the movement of re-entry into battery of the latter and which had moved into the position shown in Fig. 2, enters into the opening f and strikes the lever N, which produces the operation of the firing mechanism and in addition causes the breech block to be locked in its closed position.

The operation described is thus reproduced in a continuous manner by the recoil

of the gun barrel and its subsequent re-entry into battery.

For introducing and firing a first projectile, the breech being closed, the method of operation is as follows:

By exerting a pull upon a spring pin 70 associated with the actuating handle b⁷ (Fig. 6), the latter is released in order to allow the displacement of the casing C towards the breech. The rotation of the shaft b is transmitted by the pinion b² and the 75 wheel b³ to the crank b⁴ and by the latter to the rod E. The pull exerted by the latter upon the casing causes the spring push piece to exert a pressure upon the roller m and consequently the bell crank lever M²—M¹ 80 (Fig. 1) to swing, the effect of which swinging is to withdraw the spring bolt M.

The guides C¹ act upon the roller f¹ and compel the breech block to descend. At the same time the rollers h and i move respectively in the guides g¹ and g². In fact there are produced by hand and in the opposite direction, the effects which are produced automatically upon recoil, the casing C being displaced relatively to the gun barrel 90 A, while upon recoil the gun barrel A is displaced relatively to the casing which remains stationary.

By this means the breech is made to open, the cartridge pusher to rise and the loading belt to move forward, that is to say, the new projectile effects a translational movement so as to come immediately above the loading spoon in the vertical axial plan of the gun barrel.

By continuing to actuate the handle b⁷ the casing is brought back into its original position then causing the cartridge pusher to be lowered, a cartridge to fall upon the spoon J, the spoon to be disengaged, the recuperator K to expand, a new projectile to be driven into its lodgment and the breech to be closed automatically. The firing of the gun, which is produced by the return of the spring bolt M, is allowed to take place on account of the withdrawal of the push piece Q. When this movement is completed the spring pin of the handle b⁷ is allowed to engage in the catch b⁸, thus securing the casing in position for continuous firing.

If it is desired to carry out firing shot by shot at greater intervals of time than those which occur during continuous firing, the handle R is actuated and brought into the position shown in full lines in Fig. 3, the effect of which is to bring the push piece Q into the position shown in full lines in Fig. 1 where it forms an abutment stop for limiting the travel of the bolt M, thus preventing the production of automatic firing, while allowing the breech block to be locked. Firing may be produced by hand by actuating the handle R, which is brought from the

position shown in full lines in Fig. 3 into the position R^1 shown in dot and dash lines. This swinging movement of R withdraws the push piece Q and brings it from the position shown in full lines in Fig. 1 into that shown in dot and dash lines and consequently allows the spring bolt M to expand completely, the said bolt being thus free to actuate the striker.

10 The kinematic connection between the gun barrel and the casing which is normally secured in place but is displaceable with the whole of the mechanisms it comprises, for firing a first projectile, obtained

15 by means of the guide cams acting upon the rollers and which enables the force exerted to be rendered uniform in spite of the variations in the speed of recoil, also renders the reversibility extraordinarily easy, that is to

20 say, the displacement of the casing with its mechanisms towards the gun barrel and its return into the normal position for continuous firing by the simple manipulation of a handle and without the slightest effort.

25 In Figs. 10 to 35, A is the tube or gun barrel proper arranged in such a way as to be displaced during recoil in a cradle B .

The latter is provided with frame plates extended rearwardly along B^2 so as to form 30 a supporting and guiding member for a casing C itself adapted to form in the known manner, a support for the loader, which is in this case formed by a series of elements D formed of cylinders, which elements are 35 successively engaged in the said casing, which is provided for this purpose with the bearings C^1 , and C^2 .

As in the examples shown in Figs. 1 to 9 the casing C may be rendered movable 40 relatively to the cradle B for firing a first projectile. For this purpose, and as shown more particularly in Figs. 22 to 24 the casing is connected to the cradle by a kinematic connection which comprises a rod E pivotally connected at one end e to the casing and at the other e^1 to a crank b^6 rigidly secured to a toothed wheel b^8 keyed upon a shaft b^4 journaled in the cradle. The toothed wheel b^8 engages with a wheel b^2 keyed upon a 45 shaft which is in two sections together turning in bearings b^1 . Upon the shaft sections b and b^0 are keyed respectively the two elements b^6 and b^7 of a dog clutch, the element b^7 being adapted to slide upon the 50 shaft section b^0 , so as to compress a spring b^8 , one end of which presses upon the end of the cap b^9 rigidly secured to the cradle.

Upon the shaft section b^0 is keyed a pinion b^{10} which engages with a rack b^{11} adapted 55 to slide upon the cradle by being guided between ribs upon one of the bearings b^1 and the cap b^9 . The rod b^{11} carrying the rack is connected to the rod b^{12} of the piston b^{13} movable in a cylinder b^{14} secured to the 60 cradle B . A spring b^{15} tends constantly to

keep the piston at the end of its forward stroke in the position shown in Fig. 22.

Upon the rack bar b^{11} is provided a beak b^{16} , which, as will be shown hereinafter, is adapted to become hooked behind the beak 70 of a pawl b^{17} pivotally connected to the cradle at b^{18} and normally held pressed upon a stop b^{19} by a spring b^{20} . A cord b^{21} attached at one end of the pawl b^{17} enables the pawl and the beak b^{16} of the rack bar to 75 be disengaged from each other. The crank b^6 is adapted to engage by means of a spring buffer b^{22} in a catch b^{23} provided upon the cradle (Fig. 24).

As in the example shown in Figs. 1 to 9, 80 the breech block is again constructed in the form of a wedge or block movable in vertical grooves a (Fig. 14) in the gun barrel. It is provided at its lower part with a carriage bar F^1 provided with the rollers f^1 which, at rest (Fig. 10) are in contact with guides C^1 formed upon the casing. The carriage bar serves as attachment for pistons F^2 which form in the known manner the elements of a spring recuperator adapted to produce the 85 automatic closure of the breech. The construction of the breech is, in fact, exactly the same as in the form shown in Figs. 1 to 9. The guides C^1 are again disposed in such a way that the breech commences to open as soon as the recoil commences to take 90 place and are so shaped that the force developed for opening the breech remains practically constant during the whole of the movement of withdrawal. As mentioned above the movement of withdrawal of the breech block by means of the rollers f^1 of the carriage bar F^1 and the guides C^1 facilitates the reversibility of the displacement between the gun barrel and the casing for firing a 95 first projectile.

One of the features of the form shown in Figs. 10 to 35 is to be seen in the special construction of the loader elements and of the loading tray as well as in the combination, which is also special, of these two members and the method of mounting them upon the displaceable casing. This form, as will be seen, enables the spent cartridge case to be ejected during the time in which 100 a live projectile is loaded on to the tray.

The loader elements are each formed by a cylinder D in which are formed cavities D^1 , the number of which is one greater than the number of cartridges T , T^1 . In each of these 105 cavities which receives a cartridge are provided flexible claws D^2 which retain the cartridge case T near its front end. The rim e of the cartridge case is held in a groove d^1 formed at the rear of the said cylinder. The 110 loader element D is placed in position upon the casing and engages for this purpose by means of a rib d in a lodgment (Fig. 17) provided in the head of the trunnion D^3 which remains permanently in the bearing 115 120 125 130

- bush C^1 provided in the casing. This trunnion D^3 forms a lodgment for a spring needle D^4 , the point of which engages in a corresponding lodgment in the rib d (Fig. 10).
- 5 Similarly a hollow trunnion D^7 on the opposite side of the shaft of the cylinder D forms a lodgment for a spring needle D^6 engaging in a hollow in the corresponding base of the cylinder D .
- 10 The rear end of the cylinder is provided with a semicylindrical projection d^8 which forms a cap, as shown in Figs. 10 and 25 covering the trunnion D^5 , which projection, when the cylinder in its movement of rotation during firing has passed beyond the initial position shown in the figures, prevents any lifting movement backwards. The forward lifting movement is prevented by the rib d of the cap formed by the bearing bush 15 C^1 being held beneath the projecting edge c (Fig. 17), which edge only comprises one entry c^1 for the said rib, in the position for seating the loader element. The rotation of the loader element during firing is obtained 20 by means of a connection between the trunnion D^3 — D^4 and a roller i movable in a guide G rigidly secured to the gun barrel A . The principle of the combination by guides and rollers in the form shown in Figs 1 to 25 9 is again employed in this case.
- The roller i (Figs. 10, 19, 27 and 28) is mounted upon a shaft carried by a slide block I guided in grooves c^2 (Fig. 26) formed in the casing C and pivotally connected at its upper end at i^2 to one end of a rod I^1 the other end of which is pivotally connected to a member I^2 of the swinging lever I^2 — I^3 pivotally mounted upon the trunnion D^3 , which member is deformable under the action 40 of an abnormal resistance.
- The lever I^3 is provided upon one of its sides with a boss I^4 upon which projects towards the casing a pin I^6 . To the same side of the lever I^3 is pivotally connected by trunnions i^6 an oscillating anchor I^6 arranged 45 so as to engage in and become disengaged from alternately one of the notches d^6 of a star wheel D^5 keyed upon the trunnion D^3 .
- The oscillation of the anchor I^6 will be 50 produced by a fork-shaped spring I^7 secured in place in the support I^8 of the pivotal axis of the anchor carried by the lever I^3 . The forks of this spring engage in a cavity i^2 formed in the anchor I^6 and are curved back 55 in such a way as to be retained by the points i^3 of the anchor.
- The second anchor C^3 is pivotally connected by trunnions c^5 to a support C^4 secured to the casing C and is adapted to oscillate in a similar manner to the anchor I^6 under the action of springs C^5 retained in the support C^4 . The anchor C^3 will be first engaged in a notch d^5 of the star wheel D^5 when the anchor I^6 will be disengaged.
- 65 The loading spoon or tray J is rigidly secured to a shaft J^1 which is provided at its ends with rollers J^2 each engaging in a guide C^6 formed in the casing C . Towards the front the loading tray is provided with two rollers J^3 and J^4 (Fig. 14 and 15) which move respectively in two guides formed in arms A^1 , A^2 provided upon the gun barrel and projecting to the rear of the latter.
- The rollers J^3 and J^4 are carried by spring bolts j^3 , j^4 in such a way as to be adapted to 75 become withdrawn more or less during their guided movement in the corresponding guides.
- The tray is provided, projecting upon its upper face, with a hook J^5 which forms a 80 device for stopping and carrying along the cartridge cases of the projectiles of the cylinder when the latter are brought on to the body of the loading tray J during the intermittent rotary movement of this cylinder. 85 The movements of the tray (Fig. 14) are produced by a spring K . For this purpose it is connected at one end to the shaft J^1 and at the other end to the gun barrel A .
- The gun barrel is provided with a trough 90 forming a duct through which the spent cartridge cases fall to be ejected. The casing C is provided with a guiding device for the roller J^4 of the loading tray at the end of the recoil of the gun barrel. This device 95 comprises an incline c^4 followed by a groove c^5 (Fig. 10). To the breech block is pivotally connected at F^4 a rocking lever F^3 — F^5 one of the branches F^3 of which serves for completing the raising of the tray J when 100 the other branch F^5 has abutted beneath a boss a^1 formed upon the gun barrel.
- The firing mechanism comprises, as in the form of construction shown in Figs. 1 to 9, a locking bolt M movable in a direction 105 parallel to the axis of the gun barrel in a sleeve B^3 carried by the cradle. This bolt is arranged so as to penetrate into an opening f formed in the breech block. The locking bolt from which the breech block becomes separated as a result of the recoil of the gun barrel, becomes automatically re-engaged at the end of the re-entry into battery when the breech block is brought into the closed position, and in this movement of reengagement it acts by a suitable transmission N — O of known type upon the striker P causing the latter to be projected upon the primer of the cartridge.
- 110 Still as in the example shown in Figs. 1 to 9 the locking bolt M may be controlled by a bell crank lever M^1 — M^2 pivotally connected to the cradle under the action of which lever it is withdrawn when the casing C is displaced towards the cradle for 115 the purpose of firing a first projectile. In this movement of displacement the spring push piece Q (Fig. 23) carried by the casing acts by means of incline q upon a roller m carried by the branch M^2 of the bell crank 120

lever M^1-M^2 . The push piece Q is adapted to be displaced relatively to the casing C in order to be brought into the position shown in full lines in Fig. 23 in which it forms an abutment stop for limiting the travel of the bolt M, thus preventing automatic firing from taking place.

This firing may, however, be then produced by hand for firing shot by shot by means of a transmission comprising a handle R acting upon a pin r engaging in a groove q^1 of the push piece Q. By acting upon the handle R, it is possible as desired to put the incline q of the push piece in a withdrawn position or bring it into the position in which it acts upon the bell crank lever M^1-M^2 .

In order to describe the operation of the firearm it will be assumed that the latter has been loaded by a preliminary operation which will be described hereinafter and that the members are in the position shown in Fig. 10 in which the breech block, having been brought back into its closed position by the re-entry into battery of the gun barrel, the locking bolt M has struck the lever N of the firing mechanism causing the striker P to be projected through the medium of the lever O on to the primer of the cartridge. Only the members P, O, N and M are not shown in the position that they occupy at this moment.

As soon as the gun barrel commences to recoil under the action of the pressure exerted by the gases from the charge the breech block is compelled by the roller f^1 to follow the guides C^1 of the casing and thus gradually open by sliding in the grooves a of the gun barrel while the recuperating springs, the function of which is to cause the breech to be closed by their expansion, become compressed as a result of the descent of the cross member F^1 .

From the commencement of the recoil the loading tray J which was held at the top of the incline A^3 formed in the arm A^1 by the roller J^3 is also made to recoil with the gun barrel, the back rollers J^2 of the tray moving in slideways C^6 on the casing C.

At the same time the gun barrel guide G is displaced relatively to the roller i which controls the movements of rotation of the cylinder D. As long as the roller i is in the straight part of this guide no movement of the cylinder is produced. The recoil continuing, the tray J pivots about the roller J^3 ; as its back part becomes raised in this righting movement, the hook J^5 takes up the position shown in Fig. 15 in which it serves as an abutment stop for a new live projectile deposited upon the body of the tray as a result of the rotation of the cylinder.

And while the recoil and opening of the breech takes place the oblique back part of the guide G engages upon the roller i and

compels the latter to rise and carry along in this upward movement the slide block I, the rod I^1 and the lever I^2-I^3 . The position of the members at the commencement of this movement is shown in Fig. 19. The anchor I^6 is in engagement by one of its branches in the corresponding notch of the star wheel D^5 , while the other branch is disengaged. On the other hand the anchor C^3 engages with its two branches in the said star wheel. As shown in Fig. 27 during these upward movements of the arrangement $I-I^1-I^2$ the pin I^6 strikes the oscillating anchor C^3 , thus causing the latter to swing and allowing its upper branch to become disengaged from the notch of the star wheel. During this time the anchor I^6 is brought back into the normal position (similar to that shown in Fig. 29), by the action of the spring I^7 which had been compressed (position similar to that shown by the members in Fig. 31), the two branches of the anchor thus engaging at the same time in the notch of the star wheel. The device for driving the cylinder is then ready for the rotation of the latter to take place (Fig. 27).

During the time the recoil takes place and is completed the back rollers J^2 of the tray travel along the slideways C^6 and finally reach the back end of the latter (Fig. 11); the breech block completes its opening movement. The swinging movement of the branches S of the extractor under the action of a flange f^3 of the breech block acting upon the end s of its branches, causes the cartridge case to be extracted (Fig. 11). This ejection takes place while the tray is prepared for receiving a new projectile, which result will be obtained when the re-entry into battery commences. At the end of the recoil the front roller, J^4 of the tray J will have struck an inclined plane c^4 which, by making it compress the spring j^4 , enables it to become hooked at the top of the groove c^5 (Figs. 11 and 14).

When the re-entry into battery commences the guide G compels the roller i to descend and to carry the arrangement $I^3-I^4-I^1-I$ downwards; the members are then in the position shown in Fig. 27 and will be carried into the position shown in Fig. 19, after passing through an intermediate position, such as that shown in Fig. 28.

The anchor C^3 , which occupied the position shown in Fig. 31, being liberated so as to be able to move of its own accord, is brought by the spring C^5 into the position shown in Fig. 29. During this time the star wheel D^5 has been able to turn in the direction of the arrow (Fig. 27), the star wheel being driven through the medium of the anchor I^6 until the moment when the latter encounters with its lower branch a stop C^7 formed upon the casing, which encounter causes it to swing so that its upper branch

escapes from the star wheel D^s while the anchor C^s again becomes engaged in one of the notches of the star wheel (Fig. 19). As a result of the angular displacement of the 5 cylinder one of the cartridges T has become placed upon the tray J becoming secured beneath the hook J^s . In the downward movement on to the tray the projectile is guided near its front end beneath the guide C^s 10 (Figs. 13 and 17).

By dividing the lever I^2 — I^s into two parts, of which one I^s is adapted in the event of an abnormal resistance of the cylinder and consequently of the star wheel D^s to yield elastically relatively to the other, a safety device 15 is formed which causes the operation of the firearm to be stopped for the reason that a cartridge will not be deposited upon the loading tray. The part I^2 comprises, as 20 shown in Figs. 19 and 34, a spring bolt I^o which engages in a corresponding notch I^{10} formed in the lever element I^s . In the event of an abnormal resistance of the cylinder the beak of the spring bolt I^o escapes from 25 the notch I^{10} and the lever element I^2 is alone carried along, as shown in Fig. 34. When the re-entry into battery commences the roller J^s 30 is displaced in the branch A^s of the guide formed by the arm A' . As long as the roller remains in the horizontal part of A^s the 35 tray remains stationary and thus corresponds to the period of loading the projectile on to the tray. As soon as the sloping part of A^s becomes placed beneath the roller J^s the latter descends, carrying along the tray and the projectile into the position shown in 40 Fig. 12. During this time the spring K becomes compressed and on account of its position tends to pull the tray downwards. 45 This enables the roller J^s to descend in the slideway c^s . As soon as the roller J^s enters the branch A^s of the guide, the tray J acts as a ram. The spring K suddenly contracting brings the tray forward again with the 50 projectile it carries. At the front end of the branch A^s of the guide the roller J^s encounters a depression A^e (Figs. 12 and 14) where it is stopped; the projectile continues its forward movement under the effects of its kinematic energy and thus completes 55 its movement of re-entry into the chamber of the gun barrel.

At the end of this ramming in movement the rim t of the cartridge case encounters the 60 lateral rib s^1 of the arms of the extractor and makes the latter swing forward; the operations continue as in the example shown in Figs. 1 to 9. The breech block F having been released by the withdrawal from the 65 arms of the extractor arms S is brought back into the closed position by the action of the recuperating springs f^2 . The locking bolt M which had been withdrawn by the push exerted by a solid part of the breech 70 block during the movement of re-entry into

battery of the latter and which had moved into the position shown in Fig. 10 enters into the opening f and, as mentioned above, strikes the lever N , the effect of which is to cause the firing mechanism to be operated 75 and in addition causes the breech block to be locked in its closed position.

In rising back into this position the breech block raises the tray by means of the front block of the latter which bears upon it 80 through the medium of a spring J^s . The arm F^s of the rocking lever F^s , F^e , F^s completes the operation of bringing the tray back into the initial position shown in Fig. 10.

For introducing and firing a first projectile, the breech being closed, the method of operation is as follows:

By acting by means of the square pin b^4 upon the crank b^s in the direction of the arrow, first of all the latter is released by 85 disengaging the spring buffer b^{22} from its stop notch b^{23} ; then the movement is continued, the crank b^s being made to turn through a complete turn, the effect of which is to produce the forward and return motion 90 of the casing. The pinion b^2 thus turns through one turn but the teeth of the clutch element b^6 are withdrawn from those of b^7 and the pinion b^{10} as well as the rack b^{11} 95 remains stationary.

The forward movement of the casing produces, as in the movement of recoil of the gun barrel during normal firing, the opening of the breech and an engagement of the cylinder with a view to its subsequent 100 rotation.

In its return movement exactly the same takes place as that which occurs during normal firing upon the re-entry into battery of the gun barrel, that is to say that the projectile is deposited upon the tray by the rotation of the cylinder, then when the casing has reached its normal position (Fig. 10) the projectile is driven into the bore of the gun barrel and the breech is closed. 105

From this moment the firearm operates in a completely automatic manner until the rounds of ammunition carried by the cylinder have been all used up.

But during the recoil produced by firing 115 the first shot the beak a^s (Figs. 22 and 23) provided upon the gun barrel has carried along the beak b^{24} of the rack bar b^{11} giving the wheel b^{10} a movement of rotation. During this movement the clutch element 120 b^7 keyed upon the shaft b^o has slid upon the member b^6 without carrying it along and at the end of the recoil the beak b^{16} of the rack bar has become engaged upon the beak 125 of the pawl b^{17} , which engagement is then maintained by the spring b^{20} .

Then the following shots have succeeded each other without disengagement taking place and the gun barrel has returned to battery after the firing of the first projectile 130

of the cylinder and the ejection of the corresponding cartridge case. After the withdrawal of the empty cylinder which is effected by a simple upward pull which pushes back the pins D^4 and D^6 the cylinder loaded with projectiles is placed in position; then by exerting a pull upon the cord b^{21} (Fig. 23) the rack bar is disengaged (b^{11} — b^{16}) the effect of which is to allow the springs b^{15} to expand and to bring the said bar into the position shown in Fig. 23.

This backward movement of the rack bar produces a rotation of the two shaft sections b and b^0 and through the transmission b^2 — b^8 the actuation of the crank b^6 and the rod E in order to bring back the casing towards the cradle and to return it backwards; in other words the casing C is moved forward again then returned backwards; the stages described above are then repeated; a new projectile is loaded into the bore of the gun barrel, the breech is closed and firing takes place.

If it is desired to fire shot by shot at greater intervals than those which elapse during continuous firing the handle R is actuated, as in the form of construction shown in Figs. 1 to 9.

Two embodiments of the present invention have been described with considerable particularity and illustrated in the drawings but it is to be expressly understood that the drawings are for purposes of illustration only and not designed as a definition of the limits of the invention, reference being had for this purpose to the appended claims.

What is claimed is:—

1. An automatic gun comprising a cradle, a gun barrel mounted thereon, a casing secured to the cradle rearwardly of said barrel, said barrel being adapted to move relative to the casing during recoil, and manually operable means for moving the casing relative to the barrel.

2. An automatic gun comprising a gun barrel, a casing, means movably mounting said gun barrel and casing, said gun barrel being adapted to move relative to the casing during recoil, and manual means for moving said casing toward said barrel.

3. An automatic gun comprising a gun barrel, a casing, means movably mounting said gun barrel and casing, said gun barrel being adapted to move relative to the casing during recoil, and means including a crank arm pivotally connected to the casing for manually moving the casing toward said barrel.

4. In an automatic gun, a breech block adapted to move in a plane at substantially right angles to the longitudinal axis of the gun, means actuated by the force of recoil of the gun for moving said block to open position, firing mechanism carried by the

block, and means for automatically actuating said firing mechanism, one element of said means being adapted to lock said block against movement during firing.

5. In an automatic gun, a breech block adapted to move in a plane at substantially right angles to the longitudinal axis of the gun, means actuated by the force of recoil of the gun for moving said block to open position, manual means for moving said block to open position, firing mechanism carried by said block, a spring pressed bolt for actuating said firing means, and manually adjustable means for controlling said bolt, the latter being adapted to lock said block in closed position.

6. An automatic gun comprising a gun barrel, a casing, means mounting said barrel and casing for relative movement, cartridge carrying mechanism in said casing, a loading tray in the casing, and manually operable means for moving said casing relative to said barrel to actuate said mechanism and tray, said mechanism and tray being automatically actuated by movement of said barrel, under the force of recoil, toward said casing.

7. An automatic gun comprising a gun barrel, breech closing mechanism therefor, a casing, means mounting said barrel and casing for relative movement, means carried by the casing and having operative engagement with said closing mechanism for actuating the latter, a loading tray in said casing, and resilient means for moving said tray toward said barrel, the force of recoil of the barrel acting through said closing mechanism to store energy in said resilient means.

8. An automatic gun comprising a gun barrel, breech closing mechanism therefor, a casing, means mounting said barrel and casing for relative movement, cartridge supplying mechanism including a tray in said casing, said mechanism being adapted for automatic operation, and means carried by said casing and having operative engagement with said supplying mechanism adapted to render the force of recoil available for actuating said supply mechanism substantially constant during recoil.

9. An automatic gun comprising a gun barrel, breech mechanism therefor including firing means, a casing, means mounting said barrel and casing for relative movement, automatic cartridge supply mechanism in said casing, a bolt for actuating said firing means, means including a slidably mounted member for controlling the operation of said bolt, and manually operable means for moving said slidably mounted member to a position to render the gun semi-automatic.

10. In an automatic gun of the type embodying breech mechanism, firing mecha-

nism, cartridge supplying mechanism, and means for ramming cartridges into the gun, said mechanisms being adapted to be automatically actuated by the force of recoil of the gun, the combination with said mechanisms of a casing for housing said mechanisms, a gun cradle, means mounting the casing on said cradle, and manual means for moving said casing relative to the gun for actuating said mechanisms to fire a first projectile.

11. An automatic gun comprising a breech block, cartridge carrying mechanism, a mounting movable with said gun for the breech block, a casing for housing the cartridge carrying mechanism, said casing being adapted for movement relative to the gun and a length slightly greater than that of the cartridges carried therein, and means including curved guiding surfaces for automatically actuating said breech block and cartridge carrying mechanism, said surfaces being so shaped that the force of recoil available for actuating said block and carrying mechanism remains substantially constant regardless of the variations in speed of recoil of the gun.

12. An automatic gun comprising a breech block, said gun being provided with grooves for guiding said breech block, a carriage having rollers operatively connected to the breech block, a casing mounted rearwardly of said gun, guides for said rollers carried by said casing, the force of recoil acting through said guides and rollers to open said breech block, the opening movement of said block being initiated at the commencement of recoil, and recuperators carried by the gun for returning the breech block to closed position.

13. Magazine mechanism for an automatic gun comprising an arm operatively connected to the gun, a casing, means in said casing for guiding said arm parallel to the axis of the gun during the recoil of the latter, a carriage movably mounted in said casing, means operatively connecting said carriage and arm whereby movement of the arm moves the carriage at substantially right angles to the longitudinal axis of the gun barrel, projectile carrying means actuated by said carriage to move a projectile to a predetermined position, a loading tray in said casing, and means actuated by said arm for moving a projectile from said predetermined position onto said tray.

14. Cartridge carrying mechanism for an automatic gun comprising a plurality of longitudinally extending troughs, a loading belt carrying said troughs, a casing for said mechanism, and rollers movable on the walls of said casing for guiding said troughs in a predetermined path.

15. Loading means for an automatic gun comprising, in combination, a casing, a loading tray in said casing, said tray being provided with a beak adapted to engage said casing, a member on said tray adapted to engage the rear of a cartridge, resilient means operatively connected to said tray for moving the latter, said means being rendered ineffective to move the tray upon engagement of said beak with said casing, and means for depositing a cartridge on said tray, the weight of the cartridge serving to disengage the beak from the casing and render said resilient means effective to actuate the tray and load the cartridge.

16. In an automatic gun, ejector mechanism for spent cartridge cases comprising a casing positioned rearwardly of the gun, a spring buffer carried by the casing in the horizontal axial plane of the gun and at one side of the longitudinal axis of the latter, and means for forcing said cartridge cases rearwardly into engagement with said buffer whereby said cases are ejected from the casing.

17. In an automatic gun, a spring-locking bolt adapted to extend into an opening in the breech block of the gun, and means for withdrawing said bolt to permit a first projectile to be loaded, said means comprising a bell crank lever operatively engaging said bolt, and manually operable means for locking said bell crank lever against movement, said manually operable means being adapted for movement into an inoperative position.

18. In an automatic gun, means for preventing automatic operation of the gun to enable the gun to be fired shot by shot, comprising firing mechanism, a bolt normally automatically actuating said firing mechanism, a push piece for preventing automatic operation of said bolt, and manually operable means for moving the push piece to inoperative position.

In testimony whereof I have signed this specification.

NICOLAS EMILIEN METHLIN.
